UNITED STATES PATENT OFFICE

HENRY J. SCHLACKS, OF CHICAGO, ILLINOIS

WINDOW

Application filed October 20, 1928. Serial No. 313,886.

My invention relates in general to windows and more particularly to an improvement in the type of inset windows shown in my Patent Numbers 1,625,872 and 1,724,374, and my co-pending application, Serial Number 314-
5 857, filed on November 2, 1928. One of the principal objects of the present invention is to simplify the construction of such windows.

Another object is the provision of a more 10 efficient inset window structure which can be produced economically.

Another object is to strengthen the framework of windows of this type without increasing the cross-sectional thickness thereof.

15 Another object is the provision of an inset window of standard construction adapted to fit all types of installation.

Other objects and features of the invention will be apparent from a consideration of the 20 following detailed description taken with the accompanying drawings wherein—

Fig. 1 is an elevational view of a large inset window with my improved inset window applied thereto;

25 Fig. 2 is an irregular sectional view taken along the line 2—2 of Fig. 1;

Fig. 3 is a vertical, sectional view taken along the line 3—3 of Fig. 1;

Fig. 4 is an enlarged, sectional view of the 30 two upper corners as set along the line 4—4 of Fig. 2;

Fig. 5 is a detail of the latching mechanism;

Fig. 6 shows a modification in which the 35 angle insert is extended entirely across the web of the casement frame.

Fig. 7 is a fragmentary sectional view showing the addition of a felt liner to the inset frame;

40 Fig. 8 is a modification of the latch, and

Fig. 9 is a sectional view along the line 9—9 of Fig. 8.

As clearly shown in my prior patents and application above set out the inset window of 45 my invention is adapted to be glazed along

with the glass in a standard large window such as the usual double hung check rail type of window employed in residences and office buildings. This window comprises a wooden frame A with glass panes B and an inset window between the panes and serving as a center panel extending from the top to the bottom rail of the large window frame. This inset window comprises an inset window frame C and an inset casement frame D, 50 55 which for purposes of description will be taken up separately.

The inset frame is of the same cross-section throughout and comprises upper frame member 10, side frame members 11 and 12 and a bottom frame member 13. These four members are mitered and welded together at the corners to form a solid four-sided structure, and having angle inserts 14 at the mitered corners welded or otherwise suitably secured in place to reinforce the entire structure. This frame being of a permanent construction is glazed into the large window with the glass panes B.

Reference may now be had to Fig. 2 showing the frame in section, this figure showing the top and bottom members 10 and 13 respectively in cross-section. They are identical with the sections of the members 11 and 12 shown in section in Fig. 3, but the member 10 in Fig. 2 will be described as illustrating the cross-sectional structure of all of these members.

These members are preferably made of thin coppered steel bent from flat strip form to the shape shown. This shape includes a main web 10^a having one side formed up to produce a rectangular portion 10^b whence the strip extends back cross the web 10^a and then upwardly to form an outwardly extending flange 10^c. At the other end of the web 10^a the material is bent at right angles to form an outwardly extending flange 10^d which then extends backwardly on itself to form an inwardly extending flange 10^e. It is to be ob- 80 85 90

served that the rectangular or enlarged portion 10^b extends inwardly from the web forming a shallow channel which allows adequate room for insertion of the angles 14. The relatively wide portion resulting from the presence of the rectangular shape of one edge of the frame forms a bearing surface for the casement frame, while the control flange 10^e extending farther inwardly forms a stop for the casement thereby limiting the closing movement thereof. The edge of the flange 10^e is bent back slightly on itself as shown to avoid any sharpness thereof.

The peculiar construction of the frame is adapted to fit in for use on all sides, so that it can itself be glazed into the top and bottom rails in the same manner that the ordinary window glass is, and at the same time such window glass can be glazed into the side or upright portions of the frame. The two outwardly extending flanges 10^c and 10^d, or more properly as applied to the side members, 11^c and 11^d, form a channel as shown in Fig. 3 in which the glass B of the large window is glazed. This is done simply by inserting the glass and applying a narrow layer of glaziers' cement or putty 16 on the outside edge of the glass within the channel. At the top of the window the flanges 10^c and 10^d are extended upwardly into the glass groove in the check rail and screws 17 are extended through the web 10^a into the check rail to hold the frame in position. At the bottom the lower rail in step cut forming a shoulder against which the flange 13^c rests. The frame is held in position at this point by screws 18, and putty 19 is formed in a bevel to present a finished appearance and make the installation water and air tight at this location. The bottom strip of the frame is provided with the usual weep holes 21 at proper distances.

Returning now to the sash or casement frame this is composed of four sides including a top member 22, side members 23 and 24 and a bottom member 26. These members are of the same cross section and accordingly a description of the cross sectional shape of one member is adequate for all. Referring to the member 22 this comprises a web 22^a, right angular members 22^b and 22^c and further right angular projections 22^d and 22^e parallel with the web 22^a. Both of these side projections extend in the same direction, the inner one being somewhat wider than the outside has a narrow continuous projection 22^f resulting in the formation of a closed area having a number of utilities which will be pointed out.

The inset window glass 27 is glazed in the casement in a manner which will be made clear and its edges extend into the channel like inside portion of the casement frame and the glass lies against the edge of the inside projection 22^f. In order to form a

strong frame and at the same time permit facile glazing, corner inserts 28 are provided shaped to fill up the closed area of the casement frame. This reinforcing inset is brazed or welded to the casement frame members, and these members being mitered at the corners are also welded together to form a substantially unit structure. 70

For glazing the inset casement two of the angle inserts 28 are formed in two parts, each part being welded into its respective frame member. (Fig. 4.) A single large screw 31 is then employed to secure these two legs of the insets together to form a substantially integral structure. This arrangement results in the production of an integral three-sided frame having the third side removable therefrom. The screws 31 extend through the web of the horizontal members into the angle inserts and have their heads countersunk to avoid any possibility of binding against the inset frame. Any one of the four sides of the casement may be made to be removable for glazing purposes, but I prefer to employ for this purpose the vertical member bearing the latching mechanism, as less strain is put on the screws than if the hinge side were removable, and the arrangement makes it easily possible to glaze the casement in an emergency while it is hinged 95 to the inset frame.

As a further strengthening means a reinforcing tube 32 is placed in the closed area along the vertical hinge bearing casement member 23, this tube being framed of suitable material such as copper, steel or brass, and being brazed or welded into position preferably at the top and bottom and at one or more intermediate points. This tube extends the full length of the member 23 and the top and bottom adjacent angle inserts 28 have their vertical legs 28^a rounded to extend into the opening in the tube and so increase the strength of the structure at these two corners. Preferably the legs 28^a are welded or brazed into the ends of the tubes, and the tubes themselves are also welded or brazed against the inside of the upright member 23. The use of this tube in this fashion increases tremendously the strength 115 of the frame at this point where it is needed, without adding greatly to the weight of the swing casement. Such weight as is added, however, is close enough to the pivot point about which this member swings so that there is no magnifying thereof such as would take place if it were farther away from the pivot. This tubular insert may be employed in the other members making up the casement frame if desired, but I have found that in all cases with which I have experimented up to now adequate strength is obtained without reinforcement other than shown at these points. 120

The members making up the inset frame 130

and the casement frame are shaped so that when the leg 22^b is pressed against the casement stop 10^e the projection 22^d (or 23^d, 24^d or 26^d as the case may be) extends outwardly so as to seal off the joint between these members and prevent the possibility of moisture entering at this point. With the members in this position the inside portions of both the inset frame and casement frame are flush with each other as the drawings show. This produces a neat, attractive, but efficient and weather proof joint when viewed from either the inside or the outside. Advantage is taken of the flush character of the two frame portions to provide hinges 33—33 which are secured in position by welding or brazing the leaves to the members 11 and 23 respectively, the hinge pin being removable for separating the hinges and removing the casement. If desired, however, any other structure may be employed to secure this same effect.

I provide a latch mechanism also of simplified character, this latch mechanism comprising an eccentric latching member 34 having an integral pin 36 of circular cross-section as it extends through a steadyng block 37 and square at the end for receiving a handle 38 secured thereto by a key 39. The pin 36 also of course extends through the sash frame and has a spiral compression spring 41 secured between the handle 38 and the sash frame and encircling the pin 36. A slot 42 allows the eccentric point 34^a of the eccentric 34 to be extended behind the square projection on the inset frame to fasten the casement. The spring 41 places a tension on the eccentric 34 causing its point 34^a to bear against the inset frame and thus not only prevent rattling of the casement but also to avoid the possibility of the latch accidentally becoming unfastened.

In Fig. 6 I show a modification wherein the insert 128 has an extension 128^a extended entirely across the web of the casement frame with the exception of a narrow slot into which the edge of the glass extends. This construction may be preferred in certain cases and is slightly stronger than the construction shown in the main form. From the point of view of construction I consider that the extension 128^a is in a sense simply an addition to the insert shown in the main form instead of being an alternative form as might be supposed. In other words there need be no difference in the construction whatsoever shown in Fig. 6 and that shown in the main figures except the addition of the extension 128^a.

Under certain circumstances it may be desirable to hold the glass more securely than can be done with the relatively shallow glass groove shown in the drawings. Local regulations and ordinances for example may set an arbitrary rule which must be followed. Whatever the reason may

be I can obtain satisfactory results by employing a binding strip 43 around the edge of the glass pane, this binding strip being of suitable material such as sheet steel and having the glass secured in it, itself being secured by suitable cement in the casement groove.

Fig. 7 shows the addition of a felt line 46 to the channel portion of the inset frame. This may or may not be used depending upon the particular installation. It may be applied in any way but the simplest and what I consider now the best way of fastening it in is by means of a water proof glue. It makes the window still more air tight than it can be made without the use of the felt and also is very efficacious as a silencer.

In the modified latching arrangement of Figs. 8 and 9 a bearing block 47 is welded or otherwise secured in the closed area of the casement frame in the manner shown. This bearing block is made approximately three inches long, although the length is not of prime importance, and at the top thereof a right angular portion 47^a is provided to close off the space above the latch and an upwardly extending portion 47^b lies along the outside portion of the frame member and is secured thereto so that a strong durable structure is obtained.

A handle 48 is provided with a spindle 49 which extends through an aperture in the outside web of the frame and has its end journaled in the bearing block 47. A latching cam 51 is provided with a hub 51^a which extends above the spindle 49 and projects out through the opening in the frame, so that the latching cam is secured against turning with respect to the handle by the insertion of a pin 52, this pin extending in the manner shown through the latching cam hub and the latching spindle. In order to secure the requisite tightness and obtain a spring engagement between the latching cam and the member against which it engages a spring washer 53 is disposed about the spindle 49 between the rear face of the latching cam and the bearing block 47.

A suitable slot 54 is provided in the casement frame to receive the end of the latching cam for securing the window against opening.

Among the advantages of my present structure over those shown in my previous invention above referred to are that with this form I am able to employ thin strip material in sheet form and bend it to the shape shown so that the frame throughout is as small or smaller than the other forms and a high degree of strength is obtained. This form is of particular use in large office buildings but of course may be employed with good results with any usual type of window construction. I have described many detailed features of the invention to enable others skilled in the

art to practice the same but many of these features are shown in modified form in my prior cases. Those shown here for the first time are illustrated as one embodiment only of a novel concept which may have other and broader applications. Accordingly it is not desired to restrict or gauge the scope of the present invention from a consideration of the preceding description, but such invention is defined in the appended claims.

What I claim as new and desire to protect by Letters Patent of the United States is:

1. In an inset casement window a frame member bent to shape from sheet metal and comprising a web with inwardly and outwardly extending continuous flanges, one of which is formed hollow to provide a larger bearing surface and also serve as a reinforcement and the other of which is extended to 20 form a stop for the window.

2. In an inset casement window a frame member bent to shape from sheet metal and having a web one end of which is bent inwardly then at right angles parallel to the 25 web, at right angles, back toward the web, again at right angles along the back of the web and then outwardly at right angles again away from the back of the web, and inwardly 30 parallel to the last mentioned portion whereby an enlarged inside flange is obtained and a single thickness outside flange.

3. In an inset casement window a frame member bent to shape from sheet metal and having a web one end of which is bent inwardly then at right angles parallel to the web, at right angles, back toward the web, again at right angles along the back of the web and then at right angles again away 40 from the back of the web, whereby an enlarged inside flange is obtained and a single thickness outside flange, the other edge of the web being bent at right angles and then back on itself so that a second pair of flanges is formed, one on the outside and the other on 45 the inside.

4. In an inset casement window a casement frame member of channel cross section with an inward projection on one side of the channel forming a partially closed area which is 50 entirely closed off when the frame is glazed, and a tubular stiffening insert secured in said closed area.

5. In an inset casement window a casement frame having members of general channel 55 cross section for receiving a glass pane, and angle inserts at the corners shaped to entirely fill the casement frame members with the exception of longitudinal slots into which the edges of the glass extend.

6. In an inset casement window a casement frame having members of general channel cross section for receiving a glass pane, angle 60 inserts at the corners, a reinforcing member in one frame member extending longitudinally thereof, and means for interconnecting

the ends of the reinforcing member and the adjacent portions of the angle inserts.

7. In an inset casement window a casement frame having members of general channel cross section for receiving a glass pane, angle 70 inserts at the corners, a reinforcing member in one frame member extending longitudinally thereof, means for interconnecting the ends of the reinforcing member and the adjacent portions of the angle inserts, a reinforcing member in one frame member extending longitudinally thereof, and means for interconnecting the ends of the reinforcing member and the adjacent portions of the angle inserts.

8. In an inset casement window a casement frame having members of general channel cross section for receiving a glass pane, angle inserts at the corners shaped to entirely fill the casement frame members with the exception of longitudinal slots into which the edges 80 of the glass extend and a tubular insert in one frame member extending longitudinally thereof to the corners of the casement, the adjacent angle inserts having their adjacent legs rounded and extended into the ends of the tubular insert.

9. In an inset casement window a frame formed of sheet metal with a stop flange having its edge bent back slightly on itself for 90 the purpose described.

10. In an inset casement window a casement frame comprising a U shaped member with sidewise extending flanges from the legs of the U, both said flanges extending in the same direction so that one leg extends over the inside of the U, and a relatively short downward projection on the projection extending over the leg of the U resulting in the formation of a substantially closed space 100 within the U.

11. The combination with a frame as described in claim 13 of angle inserts designed to fill the closed area within the U.

12. In an inset casement window a casement frame having two part angle inserts at the corners, each part welded into its own frame member, and means for securing said inserts together to assemble the frame.

13. In an inset casement window a casement frame having two part angle inserts at the corners, each part secured within its own frame member, and a single large screw for each pair of inserts designed to secure such inserts together to assemble the frame.

14. In an inset casement window an inset frame formed to have a channel on the inside thereof forcing toward the casement, and a layer of packing material secured in such channel.

15. In an inset casement window a casement frame with a glass receiving groove therein, a U shaped metal binder secured on the edge of the glass and said binder with the

glass being secured within said casement groove.

16. In an inset casement frame a casement frame having a closed area therein, a latching member provided with a latching cam enclosed within said closed area, bearing means for the latching member within the closed area, an inset casement frame with means adapted to be engaged by the latching cam, and resilient means surrounding the axis of 10 the latching member for supplying tension thereto.

In witness whereof, I hereunto subscribe my name this 17th day of September, 1928.

HENRY J. SCHLACKS.
